United States Patent Office

Des. 214,597
Patented July 1, 1969

214,597

AIRPLANE

Richard T. Cathers, Fullerton, and John Morris, Newport Beach, Calif., assignors to McDonnell Douglas Corporation, a corporation of Maryland

Filed May 31, 1968, Ser. No. 12,148

Term of patent 14 years

Int. Cl. D12—07

U.S. Cl. D71—1

Des. 214,597

PAGE 2

FIG. 3

FIG. 4

FIG. 1 is a perspective view, taken from a forward position and from the top and one side of an airplane embodying the new design;

FIG. 2 is a top plan view of the airplane;
FIG. 3 is a side elevational view of the same;
FIG. 4 is a bottom plan view of the airplane;
FIG. 5 is a front elevational view of the same; and
FIG. 6 is a rear elevational view of the airplane.
We claim:

The ornamental design for an airplane, substantially as shown.
